UNITED STATES PATENT OFFICE.

WILLARD J. BELL, OF NEWAYGO, MICHIGAN.

GRINDING-MACHINE.

971,108.

Specification of Letters Patent. Patented Sept. 27, 1910.

Application filed February 11, 1909, Serial No. 477,399. Renewed March 5, 1910. Serial No. 547,559.

To all whom it may concern:

Be it known that I, WILLARD J. BELL, a citizen of the United States of America, residing at Newaygo, in the county of Newaygo and State of Michigan, have invented certain new and useful Improvements in Grinding-Machines; and I do hereby declare the following to be a full, clear, and exact description of the invention, such as will enable others skilled in the art to which it appertains to make and use the same.

My invention relates to improvements in grinding machines, and more particularly to ball and drum mills, and its object is to provide the same with various new and useful features, hereinafter more fully described and particularly pointed out in the claims.

My invention consists mainly of the combination and arrangement of a drum with conical truncated linings alternately arranged in close relation whereby communicating chambers are formed in series within the drum, said linings being supported by wood filling between the same and the interior of the drum; the device also being provided with perforated diaphragms at intervals whereby balls of different dimensions used in the successive divisions of the drum when worn down in the respective divisions will pass through a diaphragm to the next division in series, whereby I am able to feed into the device at the receiving end balls of the largest size, together with the coarser material, and the balls and material will pass from one division to another successively, and the division nearest the discharge end will contain the smallest balls.

It further consists in the combination and arrangement of parts, as will more fully appear by reference to the accompanying drawings, in which:

Figure 1 is a longitudinal vertical section of a device embodying my invention; Fig. 2 a side elevation of the same with the drum broken and shortened up; Fig. 3 a detail of one of the retaining rings for the diaphragm; Fig. 4 a ring and diaphragm attached; Fig. 5 the diaphragm 13 having the smaller openings; Fig. 6 the diaphragm 12 having the larger openings; Fig. 7, a section of the discharge screen on the line 7—7 of Fig. 1; Fig. 8 an enlarged transverse section on the line 8—8 of Fig. 1 illustrating the construction of the lining; and, Fig. 9

a transverse section on the line 9—9 of Fig. 5 of one segment of the lining.

Like numbers refer to like parts in all of the figures.

1 represents a cylindrical drum or shell of any suitable dimensions; 2 the head at the receiving end, and 3 the head at the discharge end. These heads are detachable and serve to hold the lining in place, and are also respectively provided with tubular journals 4 and 5 to receive and discharge the material. In the journal 4 is inserted a feed pipe 6 to supply the material to be ground, and the larger balls are supplied to the receiving end of the machine, preferably by removing the plug 6^a and inserting the balls through the receiving journal 4.

7 is a gear to rotate the drum, engaged by the driving pinion 8, actuated by a driving pulley 9, driven by a belt from any suitable source, not shown.

The interior of the drum is provided with a series of truncated conical linings arranged in pairs with the respective large and small ends in contact and arranged alternately, whereby a series of communicating chambers are formed extending from end to end of the drum. The open small ends of these linings constitute passages from one chamber to the next, and the large ends of the linings engage the interior of the drum. Each truncated conical lining consists preferably of six separate segments and the interior of the lining is corrugated in radial lines as illustrated in Figs. 7 and 8 to prevent the balls from sliding thereon, and to carry the balls up at the upward moving side of the drum. Each truncated conical section is held in place between the abutting ends of the adjacent sections, and the heads at the ends of the series, whereby they are retained in place without other fastening means. At intervals the drum is divided into compartments consisting of one or more of these chambers by perforated diaphragms; two being shown at 12 and 13 respectively. These diaphragms are preferably in the form of perforated disks as shown in Fig. 4 with the margins overlapping the small ends of the conical linings and beveled to fit the same.

Each diaphragm is secured in place by a ring 15, having a beveled margin opposite the beveled margin of the respective diaphragm and bolts extending through the

rings and diaphragms close inside the small ends of the conical linings, as illustrated in Figs. 1 and 5. The diaphragm 12 is provided with openings somewhat smaller than the balls when the latter are first placed in the machine, and the diaphragm 13 has still smaller openings. Any number of these diaphragms may be used as found convenient and preferable, each succeeding diaphragm having smaller openings to permit the balls to pass therethrough, as they become reduced in size by wear. The exit opening in the head 3 is covered by a cap having a cylindrical portion extending inward and provided with narrow slits or openings through which only the sufficiently pulverized material can escape into the hollow journal 5 at the discharge end of the machine. Wooden filling 11 is provided between the lining and the drum which filling tends to prevent vibration of the machine and also prevents any leakage of material through the joints of the lining from accumulating between the lining and the drum. This filling is held in place by the lining and drum without any other fastening means. It will be noted that the lining and filling is retained in place without special fastening means and can be easily removed or replaced by merely taking off a head, thus being very easily assembled, or repaired, as occasion requires, and there are no bolts or fastenings to wear out or become loosened. The form of these double truncated conical chambers is such that the bulk of the material and balls therein is carried nearer to the axis of the drum than in a drum having a plain cylindrical interior. The drum is thus more easily rotated, resulting in a saving of power. The action being mainly where the balls roll down over the surface of the mass thereof, is substantially the same as though the drum were cylindrical inside and at the same time a much less quantity of balls are required.

While this machine may be used as a ball mill for various materials, it is mainly intended for pulverizing cement, using pebbles therein for balls. These pebbles by use are gradually reduced in size and as they become so reduced, they will pass through the openings in the first diaphragm and into the next compartment and being therein again gradually worn down, will pass from thence into the next compartment and so on according to the number of compartments and size of openings in the diaphragms, being finally retained in the last compartment until worn down sufficiently to escape with the material, or removed therefrom as occasion may require.

What I claim is:—

1. In a mill of the class described, a cylinder, a lining therefor comprising a plurality of sections, each section being composed of 65 a plurality of division plates, each section

having an inclined member and a member at the extremity of said inclined member which latter is parallel with the surface of the cylinder, lies against the inner surface thereof, and abuts against the like member of the adjacent section. 70

2. A ball and drum mill, comprising a drum having a series of communicating chambers, perforated diaphragms between the respective chambers, said diaphragms 75 having openings large enough to permit the balls to pass successively therethrough when the balls have been reduced by wear in each chamber, means for rotating the drum, and means for supplying balls to the first chamber of the drum. 80

3. A ball and drum mill, comprising a drum having a series of chambers communicating by means of axial openings of less diameter than the chambers, diaphragms at 35 intervals in the drum and having progressively reduced openings therein large enough to permit balls of the sizes commonly used to pass successively therethrough after said balls have been reduced in size 90 by use, means for rotating the drum, and means for supplying balls and material to said drum.

4. A ball and drum mill, comprising a drum, and a lining for the drum consisting of 95 separate truncated conical sections arranged end to end, each section having its small end abutting against the small end of the adjacent section, and its large end abutting against the large end of the adjacent 100 section, and means for securing the end sections of the series in place.

5. A ball and drum mill, comprising a drum, a lining for the drum consisting of alternately disposed truncated conical portions, said portions engaging end to end, a filling between the lining and drum, and held in place thereby, means for rotating the drum, and means for supplying balls and material to the drum. 105 110

6. A ball and drum mill, comprising a drum, and a lining for the drum consisting of separate truncated conical sections engaging the interior of the drum at their larger ends, each section being divided longitudinally into segments and each section abutting against the respective adjacent section at the respective ends, and the end sections of the series held in place by removable heads to the drum. 115 120

7. A ball and drum mill, comprising a drum having detachable heads, a lining consisting of a series of alternately arranged truncated conical sections each section being radially corrugated and abutting end to end with adjacent sections and held at the ends of the series by the heads, means for rotating the drum, and means for supplying balls and material to said drum. 125

8. A ball and drum mill, comprising a 130

drum having tubular journals, a lining to said drum consisting of a series of oppositely arranged truncated conical portions, a perforated diaphragm engaging the small 5 end of a cone and a ring secured to the diaphragm and engaging the small end of the adjacent cone, and means for attaching the ring and diaphragm to each other.

9. A ball and drum mill, comprising a 10 drum, a lining consisting of a series of oppositely arranged truncated conical portions, wood filling between the lining and drum, perforated diaphragms at intervals in the drum, detachable heads to the drum having 15 tubular journals, a feed pipe opening into one journal, and an exit screen between the other journal and the interior of the drum.

10. A ball and drum mill comprising a drum having removable heads, a removable lining consisting of truncated conical sections held in place solely by the drum and heads, a filling between the lining and drum, perforated diaphragms at intervals in the drum engaging the small end of a respective section of lining, and a ring attached to each 20 diaphragm and engaging the small end of the adjacent section of lining, and means for rotating the drum.

In testimony whereof I affix my signature in presence of two witnesses.

WILLARD J. BELL.
